UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed May 10, 1920. Serial No. 380,285.

To all whom it may concern:

Be it known that I, ALFRED COTTON, a citizen of the United States, residing at St. Louis, Missouri, have invented a certain new

5 and useful Improvement in Water-Tube Boilers, of which the following is a full, clear, and exact description, such as will enable others skilled in the art to which it app pertains to make and use the same.

10 This invention relates to water tube boilers of the type that are adapted to be fired from the front and from the rear of the boiler, and which comprise a center combustion chamber arranged between two units

15 composed of cross drums and banks of upright water tubes.

One object of my present invention is to provide a boiler that is superior to the boilers of this general type now in use, in that 20 it produces drier steam, it insures complete combustion before the gases become chilled below their ignition temperature, and it allows of great power being concentrated in small floor space.

25 Another object is to provide an efficient superheater boiler of the general type referred to, in which the superheater is compact, accessible and so arranged that the flow of the hot gases over the superheater 30 elements can be accurately controlled, thereby enabling the degree of superheat attained to be easily regulated.

Another object is to provide a water tube boiler that is equipped with a submerged 35 water drum combined with a baffle in such a manner that it performs the function of a horizontally-disposed shelf on the baffle.

Other objects and desirable features of my invention will be hereinafter pointed out.

40 Another object is to provide a water tube boiler having a crossed water flow through the combustion chamber, which is so constructed that short tubes can be used to interconnect the front and rear units of the 45 boiler, thereby overcoming the necessity of decreasing the length of the largest proportion of the tubes of the boiler, as is necessary in the boilers of this general type heretofore in use.

50 Another object is to provide a boiler having crossed water tubes in the combustion chamber, which is constructed in such a manner that said crossed tubes virtually

form radiant heat banks in the combustion chamber which absorb very little heat by 55 convection and reduce the gas temperature very little.

To this end I have devised a boiler that comprises a centrally located combustion chamber and two separate units arranged 60 at the front and at the rear of said combustion chamber and connected with each other in such a manner that the water will circulate through the boiler without encountering sufficient restriction to flow to cause 65 water to be carried over into the steam space or spaces from which the supply of steam is taken or to cause the level of the water in some of the steam-and-water drums to drop sufficiently to result in the upper ends of 70 some of the water tubes becoming dry and overheated. Instead of using tubes of maximum length and of considerably greater length than the largest number of tubes of the boiler to connect the front and rear units 75 of the boiler together, as has heretofore been the usual practice, the means that is used in my boiler for interconnecting the front and rear units consists of groups of short tubes 80 combined with submerged water drums in such a way as to form a pathway resembling the figure 8 in outline through which the water circulates from one unit to the other.

The short tubes forming part of the unit interconnecting means of the boiler are 85 crossed in the combustion chamber of the boiler, and said tubes are so arranged with relation to each other and the number of such short tubes that are used is such that 90 said crossed tubes constitute virtually a radiant heat bank, notwithstanding the fact that they are arranged in the main path of the gases. Preferably said short tubes are spaced double the usual distance apart transversely of the boiler and the tubes of each group are spaced widely apart so as to not have a sufficient number of water tubes in the combustion chamber to greatly reduce the temperature of the gases or interfere 95 with the combustion, as would occur if a large number of closely spaced water tubes were arranged in the combustion chamber. Consequently, my boiler has the following 100 desirable characteristics which distinguish it from prior boilers of this general design: 105 1st. A crossed water flow through the

combustion chamber to interconnect the front and rear units.

2nd. An interconnecting means between the front and rear units consisting of short 5 water tubes and submerged water drums.

3rd. Radiant heat banks in the combustion chamber that absorb very little heat by convection and reduce the gas temperature very little and which are formed by groups 10 of tubes that are spaced widely apart.

In addition to having the desirable features above mentioned, my boiler is so designed that the submerged water drums support the first baffles of the two units and 15 they form the equivalent of baffle shelves for directing the gases among the tubes of the second banks of the units, said submerged drums being preferably arranged so that they are not exposed to the intense heat of 20 the fire or combustion chamber.

Figure 1 of the drawings is a vertical longitudinal sectional view of a superheater boiler constructed in accordance with my invention.

25 Figure 2 is a diagrammatic view, illustrating the circulation of the water through the boiler; and

Figure 3 is a vertical longitudinal sectional view of a boiler of the kind shown 30 in Figure 1, without a superheater.

Referring to the drawings which illustrate the preferred form of my invention, A designates the combustion chamber of the boiler which is arranged between two units 35 composed of transversely-disposed drums and banks of upright water tubes, said combustion chamber being adapted to be fired from the front and from the rear end of the boiler, as is usual in boilers of this general 40 type. Each of the units above referred to comprises a mud drum B, and two elevated steam-and-water drums C and C'. Each of said units also comprises four banks of upright water tubes, a rear bank 1, a third bank 45 1^a, a second bank 2 and a front radiant heat bank composed of water tubes arranged in such a manner that the water will circulate upwardly from the mud drum B of the front unit into the inner drum C of the 50 rear unit and the water that is supplied to the mud drum B of the rear unit will circulate upwardly from same into the inner drum C of the front unit. I prefer to combine submerged water drums D with the 55 water tubes of the front banks of both units and connect said submerged drums with particular mud drums with which they operate by sets of short crossed tubes 3. For example, the submerged drum D, which 60 operates with the mud drum of the front unit, is connected with same by tubes 3 that lead upwardly and rearwardly from the mud drum of the front unit. And the other submerged drum is connected with the mud 65 drum of the rear unit by short tubes 3 that

lead upwardly from said rear unit mud drum. The submerged drum D that cooperates with the mud drum of the front unit is connected with the inner drum C of the rear unit by a set of short upflow 70 tubes 4 and the other submerged drum is connected with the inner drum C of the front unit by a similar set of short upflow tubes 4. By constructing the front banks or radiant heat banks in this manner, I 75 greatly reduce the cost of manufacturing the boiler. For example, if long tubes or continuous tubes were used to connect the mud drum of one unit with the inner steam-and-water drum of the other unit, said 80 crossed tubes would be much longer than the tubes in the other banks of the boiler. As the length of said crossed tubes would be limited to commercial lengths, the tubes of the other banks which comprise by far the 85 largest number of tubes in the boiler, would necessarily have to be short. This would greatly increase the cost of the boiler, because the expense of drilling the tube holes in the drum, and of bending, assembling and 90 expanding the tubes in the tube holes is so much more costly than a small increase in the length of the tubes. Accordingly, the least costly boiler is one in which the largest 95 proportion of the tubes are the longest. My 100 boiler has this characteristic, for long tubes are used to form the second, third and fourth banks and short crossed tubes which form the smallest proportion of the tubes of the boiler are used to connect the two units together. The tubes of the rear bank 1 of each unit are connected at their upper ends to the outer drum C' of said unit, and the tubes of the third bank 1^a are connected at 105 their upper ends to the inner drum C of said unit. All of the tubes of the second bank 2 of each unit have their upper ends connected to the inner drum C of the unit of which they form a part, and the lower ends of the tubes of the rear bank 1, the third bank 1^a and the second bank 2 of each unit are connected to the mud drum B of the unit. The inner and outer drums C and 110 C', respectively, of each unit are directly connected with each other by water circulators 5. Most of the upper short tubes 4 that form part of the front bank of each unit are connected directly from the submerged drum D of the unit to the inner drum C of the same 115 unit, but some of the short upper tubes, those designated by the reference character 4^a, are so arranged that a circulation is established between the submerged drum of the front unit and the inner drum C of the rear unit and between the submerged drum of the rear unit and the inner drum C of the front unit.

120 Each unit of the boiler is provided with a front baffle 6 arranged at the rear side of the set of short tubes 3 of said unit and ex- 125

tending upwardly from the mud drum B of said unit, over the submerged drum D of the other unit and terminating some distance below the inner drum C of the unit of 5 which said baffle forms a part. Each of the units is also provided with a second baffle 6^a that extends downwardly from the drum C at the rear side of the second tube bank 2 and terminates at a point above the mud. 10 drum. The steam-and-water drums C and C' of the respective units are preferably connected together in such a manner that the steam which collects in the inner drum C of the front unit can flow into the outer 15 drum C' of the rear unit through steam circulators 7, and the steam which collects in the inner drum C of the rear unit can flow into the drum C' of the front unit through steam circulators 7.

20 The boiler shown in Figure 1 is provided with a superheater composed of substantially horizontally-disposed tubes 8 that lead from the outer drums C' to a steam drum E from which the supply of steam is taken 25 through an outlet 9, said superheater elements being arranged at the top of the boiler in a chamber provided with an inlet 10 located at approximately the center of the boiler. The superheater chamber is provided with two outlets 11 arranged between the drums C and C' of the respective units, and valves or dampers 12 are provided at 30 said outlets so as to control the flow of the hot gases over the superheater elements.

35 When the boiler is in operation the gases flow upwardly through the combustion chamber A over the tubes 3 and 4 of the front banks of both heating units of the boiler. Upon reaching the upper end of the 40 combustion chamber the gases split up into three streams, two of which streams circulate downwardly among the tubes of the middle banks of the units and then upwardly among the tubes of the rear banks 45 of said units to gas outlets 13 at the upper end of the boiler and the other stream entering the superheater chamber wherein it divides and flows laterally in opposite directions over the superheater elements to the 50 outlets 11 of the superheater chamber. The circulation of the water through the boiler is indicated clearly by arrows in Figure 2, wherein it will be noted that the water circulates through the boiler in a path that is 55 substantially the shape or outline of the figure 8, the flow being upwardly from the mud drum of the front unit to the submerged drum which co-operates with said front unit mud drum, upwardly from said 60 submerged drum to the inner drum C of the rear unit, downwardly to the mud drum of the rear unit, upwardly and across to the submerged drum D which co-operates with the mud drum of the rear unit, upwardly 65 from said submerged drum to the inner

drum C of the front unit and downwardly from said drum C to the mud drum of the front unit.

In the boilers of this general type now in use, which boilers are commonly referred to as A type boilers, any provision for heating the feed water before it enters the general circulation would require considerable addition to the space required; another objectionable feature of such boilers is that the effective height of the combustion chamber is only about one-half the real height of the combustion chamber, owing to the fact that the combustion chamber is bounded at the front and at the rear by full banks of water tubes that cool the gases before they have risen to the top of the combustion chamber. When such boilers are equipped with a superheater, the superheater elements are generally placed between the tube banks, 80 thus making them difficult of access, and another objectionable feature of such boilers is that there is a tendency for water to accumulate in the center drum, due to the fact that most of the steam and water is discharged into the center drum and is conducted from said center drum to the outer drums through circulators of small cross-sectional area that materially restrict the flow of the water from the center drum to 85 the outer drum. In other words, there is a tendency for the water level in the center drum to rise abnormally. This reduces the steam disengaging surface and the steam-and-water separating space so that there is 90 a tendency to carry much water with the steam flowing into the outer drums of the boiler. Also, as the water level rises in the center drum, it materially falls in the outer drums, with the danger of allowing the 95 upper ends of some of the tubes in the outer banks to become dry and overheated.

100 My improved boiler overcomes the objectionable features or characteristics of the so-called A type boilers previously referred to, and is superior in many other respects to any water tube boiler heretofore devised of the type in which the combustion chamber is adapted to be fired from the front and from the rear end of the boiler. In my boiler, which may be termed an X type boiler, the circulation roughly describes the figure 8, instead of there being two circuits, as in the A type boiler, but from each of the submerged drums D one longitudinal 110 row of tubes 4^a is taken back to the steam-and-water drum C above the mud drum which communicates with the particular submerged drum from which the longitudinal row of tubes 4^a lead. This helps towards 115 balancing the circulation, and in combination with the bulk of the circulation passing or crossing from back to front and from front to back, it tends to keep an even water level in all the steam-and-water drums, 120 125 130

thereby insuring the production of dry steam.

It is usual in boilers of this general type, including Stirling boilers, to provide horizontal shelves behind the baffles to cause the gases to keep within the tube banks as much as possible. In my boiler the submerged drums D take the place of these baffle shelves very efficiently while providing some heating surface at the same time. Moreover, as the submerged drums D are supported by water tubes, the supporting means for said drums are not apt to burn away rapidly, as is the case with cast iron or steel beams and supporting rods, such as are generally used for supporting the shelves that are generally arranged behind the baffles of upright tube boilers. The sets of short tubes 3 and 4 that co-operate with the submerged drums D are so disposed as to be well adapted to carry baffles which protect said drums, thereby eliminating the possibility of the submerged drums D becoming overheated to such an extent that they bulge or rupture. The gases which strike the drums D are somewhat cooled by having passed over some tube heating surface, and there is not the objection to these gases impinging on the drums that there is to exposing them to direct radiant heat, as in boilers of the type wherein a central drum is exposed to direct or radiant heat from the furnace. As the bottoms of the drums D are not in the direct path of the gases, the longitudinal seams of said drums may be conveniently placed on the undersides of same, but said seams can also be placed on the top sides of the drums and the drums covered with brick or tile for protection, the drums D being so arranged that ample passages are provided at the points where the drums are located for convenient inspection of said drums.

In boilers of this general type, wherein drums are connected with banks of bent tubes, the tubes are usually disposed in pairs of circumferential rows. The two rows of a pair are close together, but the space between the pairs of rows is sufficient to allow of the passage of a tube for removal and renewal. In both the upper and lower sets of tubes 3 and 4 of the front banks of both units advantage is taken of this arrangement, in that one row of a pair crosses the other row. The same arrangement is used with the superheater tubes 8 and the tubes 7 which carry steam from the inner steam-and-water drums C to the outer drums C'. It will therefore be seen that in my boiler the rows of tubes of the front banks of each unit are about twice as far apart longitudinally as those of the rear banks of the units, except at the points where the tubes of the sets 3 and 4 cross each other. As these tubes are all far apart circumferentially (so to speak), there is generally a considerable distance be-

tween any two tubes of the boiler. Further, while there are four longitudinal rows of tubes in the upper and lower sets of the front banks of each unit, they are only equal to two full or usual rows of tubes. Therefore, the chilling effect of the tubes 3 and 4 on the gases is very small compared with the usual method of allowing the gases to directly enter two compact banks of six or seven longitudinal rows of tubes each; and the effective height of the chamber A, wherein combustion can properly continue, is the full height of the boiler, or, about twice the effective height of the combustion chamber of an A type boiler. In other words, my boiler has small banks of water tubes in the combustion chamber which virtually form radiant heat banks that absorb very little heat by convection and reduce the gas temperature very little, the tubes constituting said radiant heat banks being spaced relatively far apart and the number of said tubes being materially less than is used in boilers of this general type for connecting the front and rear units together.

In my boiler there are as many tubes connecting the submerged drums D with the inner steam-and-water drums C as there are between the mud drums B and the submerged drums. Consequently, the circulating area is ample and unrestricted. The flow from the tubes 4 to the descending flow tubes of the boiler is simply across the drums C and is entirely unimpeded. The tubes of the second banks 2 are preferably so arranged that some of said tubes will be upcomers and some downcomers, according to the rate of driving to which they automatically adjust themselves. Here again there is no impediment to free circulation. The most rapid circulation (due to the most violent ebullition) is upwardly through the tubes 3 and 4 and across the inner drums C to the downcomer banks, the circulation through these parts of the boiler being free and unrestricted.

The outer steam-and-water drums C' of my boiler act as steam separating drums, as well as to form economizers with the rear banks 1 of the respective units in the manner generally preferred in this particular type of boiler. By combining the outer circulating bank of each unit with the economizer bank into one pass, I obtain a counter flow through the economizer bank of each unit,—the gases flowing upwardly and the feed water downwardly—so that the hottest gases of the last pass of each unit encounter the hottest water and the cooler gases the cooler water which favors efficient heat transfer from the gases to the water. Also as it is objectionable to have the feed water enter the tubes so cold as to cause condensation on the outside of the tubes, with consequent rapid corrosion, I place a sufficient

number of water circulators 5 between the drums C and C' of the respective units to produce sufficient circulation to insure that the water descending the economizer banks

5 1 shall be warm, which is in accordance with recognized good practice.

In my boiler it is practicable to use the drums C' as economizer and steam separating drums in conjunction with the economizer tube banks 1, because I can do so while keeping the whole boiler very compact. This is due to my improved method of conveying the steam from the inner to the outer drums, whereby I am enabled to get 10 these drums very close together. Instead of connecting the steam circulators from the inner drum of one unit to the adjacent outer drum of said unit, I prefer to connect the inner drum C of the front unit to the outer drum C' of the rear unit and connect the inner drum C of the rear unit to the outer drum C' of the front unit, as previously described. By making my steam connections in this manner I take the steam 15 from the inner drums at points removed from where the water is thrown by violent circulation from the tubes 4 of the boiler. In the usual A type boiler and in Stirring boilers generally the steam is taken 20 from a point directly or diametrically opposite the inlet of water of violent circulation, so that considerable water is carried over with the steam. By cross connecting the drums C and C' in the manner above de-

30 scribed I avoid this objectionable characteristic, as well as economize space. It also provides a convenient means for carrying a refractory shield 14 for protecting the lower side of the superheated steam drum E.

40 The general arrangement of the boiler permits of a convenient design of superheater elements which are accessible and wherein some of the gases are shunted through the superheater chamber. This enables the flow 45 of the gases over the superheater to be controlled by dampers 12 so that the degree of superheat can be regulated very closely. It will also be noted that the steam which enters the outer drums C' is discharged in the 50 opposite direction into the superheater tubes 8, thus eliminating the possibility of water being carried out of the drums C' with the steam. I also believe that it is new to use the outer feed water and steam separating 55 drums C' of the boiler as inlet headers for the tubes 8 of the superheater.

In Figure 3 of the drawings I have shown a boiler of the same construction as the one illustrated in Figure 1, except that it is not 60 provided with a superheater. In the boiler shown in Figure 3, the steam generated in the boiler is taken from the outer drums C' of both units through steam outlets 15 and the spaces between the drums C and C' of 65 each unit and between the inner drums C of

the respective units are closed by shields 16 and 17, respectively, the shields 16 resting upon the water circulators 5 and the shield 17 resting upon the tubes 4.

Having thus described my invention, what 70 I claim as new and desire to secure by Letters Patent, is:

1. A water tube boiler of the type in which the combustion chamber is adapted to be fired from the front end and from 75 the rear end of the boiler, comprising separate and distinct units arranged at the front and at the rear ends of the combustion chamber and each composed of a mud drum, elevated cross drums and banks of upright 80 water tubes that connect said cross drums with said mud drum, separate banks of crossed tubes in the combustion chamber each of which is connected at its lower end to the mud drums of one of the units, separate submerged water drums connected with the upper ends of said crossed tubes, and banks of up flow tubes leading from said submerged drums and so arranged that the water which is supplied to the submerged drum of one unit will circulate through one of the elevated drums of the other unit, said crossed tubes being spaced 85 apart double the usual distance.

2. A water tube boiler provided with a center combustion chamber that is adapted to be fired from the front and from the rear end of the boiler, units arranged at the front and at the rear of said combustion chamber and each comprising a mud drum, at least two elevated cross drums and upright water tubes connecting said cross drums with said mud drum, banks of crossed water tubes in the combustion chamber whose lower ends are connected with 100 the mud drums of the respective units, submerged water drums connected to the upper ends of said banks of crossed tubes, the crossed tubes constituting said banks being 105 spaced double the usual distance apart, and upflow tubes that connect each of said submerged drums with the inner cross drums 110 of each unit.

3. A water tube boiler provided with a centrally located combustion chamber, units arranged at the front and at the rear of said combustion chamber and each comprising a mud drum and two elevated steam-and-water drums, banks of crossed tubes in the combustion chamber that conduct the water 115 upwardly from said mud drums, baffles arranged at the rear sides of said tube banks, submerged drums connected to the upper ends of said tube banks and so arranged that they form rearwardly-projecting shelves on said baffles, and upflow tubes arranged so as to connect the submerged drum 120 of each unit with one of the steam-and-water drums of the other unit.

4. A water tube boiler provided with a 125

center combustion chamber, units arranged at the front and at the rear of said combustion chamber and each comprising a mud drum, two elevated steam-and-water drums, 5 a rear bank of tubes and an intermediate bank of tubes connecting said steam-and-water drums with said mud drum, banks of crossed tubes in the combustion chamber of the boiler whose lower ends are connected 10 to the mud drums of the respective units, submerged water drums connected to the upper ends of said banks of crossed tubes, upflow tubes for connecting the submerged drum of each unit with the inner steam-and-

water drum of the other unit, a superheater 15 chamber arranged at the top of the boiler and comprising a superheater drum, superheater tubes that connect the outer steam-and-water drums of the respective units with said superheater drum, steam circulators in the superheater chamber that connect the inner steam-and-water drum of each unit with the outer steam-and-water drum of the other unit, and means for regulating the flow of the gases through said 20 superheater chamber. 25

ALFRED COTTON.
